CHRISTMAS ORNAMENT

Dario Moranduzzo, Via Aretina 161,
Florence, Italy

Filed May 9, 1967, Ser. No. 7,028

Term of patent 14 years

(Cl. D29—1)

FIG. 1

FIG. 2

FIG. 3

The Christmas tree light bulb is shown in broken lines in FIGURES 1 and 2 for illustrative purposes only.

I claim:

The ornamental design for Christmas ornament, as shown and described.
